US0D1025600S

(12) **United States Design Patent** (10) **Patent No.:** **US D1,025,600 S**
(45) **Date of Patent:** **** May 7, 2024**

(54) **STORAGE CONTAINER**

- (71) Applicant: **TECHTRONIC CORDLESS GP**,
Anderson, SC (US)
- (72) Inventors: **Tyler H. Knight**, Greenville, SC (US);
Jeffrey Groves, Greenville, SC (US); **J. Porter Whitmire**, Greenville, SC (US);
J. Luke Jenkins, Williamston, SC (US); **Stephen A. Huggett**, Anderson, SC (US); **Brianna E. Williams**, Greenville, SC (US); **William J. Saunders**, Anderson, SC (US); **Charles Moody Wacker, II**, Anderson, SC (US)
- (73) Assignee: **Techtronic Cordless GP**, Anderson, SC (US)
- (**) Term: **15 Years**
- (21) Appl. No.: **29/767,056**
- (22) Filed: **Jan. 20, 2021**
- (51) LOC (14) Cl. **03-01**
- (52) U.S. Cl.

(57) **CLAIM**

We claim the ornamental design for a storage container, as shown and described.

DESCRIPTION

FIG. 1 is a top perspective view of a storage container showing our new design.

FIG. 2 is a bottom perspective view of the storage container of FIG. 1.

FIG. 3 is a front view of the storage container of FIG. 1.

FIG. 4 is a rear view of the storage container of FIG. 1.

FIG. 5 is a first side view of the storage container of FIG. 1.

FIG. 6 is a second side view of the storage container of FIG. 1.

FIG. 7 is a top plan view of the storage container of FIG. 1; and,

FIG. 8 is a bottom plan view of the storage container of FIG. 1.

Portions of the storage container shown in dash-dash lines form no part of the claimed design. Portions of the storage container shown in dot-dash lines indicate boundaries of the claimed portions and form no part of the claimed design.

1 Claim, 8 Drawing Sheets
